UNITED STATES PATENT OFFICE.

THOMAS H. LATIMER AND FRANK A. FLETCHER, OF WATERTOWN, NEW YORK, ASSIGNORS TO THE BAGLEY & SEWALL COMPANY, OF SAME PLACE.

PAPER-MAKING MACHINE.

SPECIFICATION forming part of Letters Patent No. 448,441, dated March 17, 1891.

Application filed November 28, 1890. Serial No. 372,791. (No model.)

To all whom it may concern:

Be it known that we, THOMAS H. LATIMER and FRANK A. FLETCHER, of Watertown, in the county of Jefferson, in the State of New York, have invented new and useful Improvements in Paper-Making Machines, of which the following, taken in connection with the accompanying drawings, is a full, clear, and exact description.

10 This invention relates to the axial supports of the lower couch-roll of a Fourdrinier paper-making machine, said roll carrying the endless wire-cloth which receives the diluted pulp and forms the same into paper. Said 15 wire-cloth has to be occasionally renewed, and to remove the old and introduce the new wire-cloth it was hitherto necessary to lift the lower couch-roll out of its axial bearings to an elevation above the top of the frame in order to allow the wire-cloth to be slipped onto the said roll endwise of the latter.

The object of this invention is to obviate the necessity of lifting the couch-roll above the frame of the machine when desired to renew 25 the wire-cloth, and thus facilitate the latter operation and reduce the loss of time required to effect the renewal of the wire-cloth in the machine; and to that end the invention consists, essentially, in the combination 30 of the main supporting-frame formed with a depression in the top of its side wall under the axis of the lower couch-roll and an axial support for the couch-roll detachably connected to the frame, as hereinafter more fully 35 described, and specifically set forth in the claims.

Our invention is susceptible of several modifications without departing from the spirit of the invention.

40 In the annexed drawings, Figure 1 is a side elevation of that part of a Fourdrinier paper-making machine to which our invention pertains. Fig. 2 is a top plan view of the removable frame-section with the end of the couch-roll mounted thereon shown in dotted lines. Fig. 3 is a detached perspective view 45 of the removable frame-section or truss which spans the opening or depression made in the top of the frame to obviate the necessity of 50 lifting the couch-roll above the top of said frame. Fig. 4 is a detached perspective view

of the preferred form of the axial-support or journal-bearing of the couch-roll. Figs. 5, 6, and 7 are side views of modifications of our invention, and Fig. 8 illustrates the mode of 55 applying or removing the wire-cloth to or from the couch-roll.

Similar letters of reference indicate corresponding parts.

A represents the main supporting-frame of 60 the machine, and C denotes the lower couch-roll, on which the endless wire-cloth *a* travels. The top of the side wall of said frame we form with an opening or depression *d* directly under the axis of the aforesaid couch-roll, 65 which opening or depression is of such a depth and length as to bring it beneath the plane of the bottom portion of the couch-roll. The axial support of the couch-roll over the depression *d* is detachably connected to the 70 frame, and may be constructed in various ways.

Figs. 1 to 4 illustrate our preferred form of the said axial-support, and it consists of a truss or frame-section *b*, which spans the depression *d* and rests with its ends on the top of the frame, and is preferably countersunk therein to bring the top of the truss *b* flush with the top of the frame, as shown in Fig. 1 of the drawings. The joints of the seats of 80 the truss are so made as to allow the truss to be slipped sidewise out from the frame. To retain the truss on the frame, a dowel-pin may be inserted in the end of the truss at the tending side of the couch-roll and into the 85 subjacent part of the frame. The opposite end of the truss we prefer to fasten to the frame by means of a tap-bolt, as indicated by dotted lines in Fig. 1 of the drawings.

The journal-box *c* of the couch-roll we 90 prefer to mount removably on the truss by providing the top of the latter with a socket *s* and forming the bottom of the journal-box *c* with a hub *t*, which enters the aforesaid socket and thus prevents lateral displacement 95 of said journal-box.

In replacing the wire-cloth *a* a stout metal sleeve *l* is slipped with one end onto the trunnion *n* of the couch-roll, as shown in Fig. 8 of the drawings and into the opposite end of 100 the sleeve is inserted the end of a pole passing through the wire-cloth fold. By slightly

lifting the outer end of the said pole the end of the couch-roll C, connected to said pole as aforesaid, is raised sufficiently to relieve the journal-box c and truss b of the weight of the couch-roll and allow the said journal-box to be lifted and slipped sidewise from the truss, and said truss to be lifted and removed sidewise out from the main frame A after the tap bolt is removed and the dowel-pin deprived of its hold. The removal of the truss b allows the wire-cloth to be passed sidewise through the opening or depression d and shifted onto the couch-roll lengthwise of the latter. After the wire-cloth is placed in its requisite position on the couch-roll the truss b is readily replaced across the depression d, and the journal-box mounted and secured to the top of said truss to support the couch-roll by its trunnion. The sleeve l is then to be removed from the said trunnion. The journal-box c may be made small enough to come within the circumference of the couch-roll and allow it to be left on the trunnion of the couch-roll during the aforesaid operation of applying the wire-cloth. The bottom portion of the journal-box c may be formed integral with the truss b, as represented in Figs. 5 and 6 of the drawings; or the entire journal-box may be formed directly on the truss, as shown in Fig. 7 of the drawings. In either case it will be necessary to form the truss with an elevated central portion, as shown. The end of the truss at the driving side of the couch-roll may be further restrained from being lifted from the frame by the tension of the wire-cloth, by inserting said end of the truss into a transverse groove or under an overhanging shoulder i, as shown in Fig. 7 of the drawings. Furthermore, the truss b need not completely span the depression d, but may be simply of the form of a pedestal P, mounted in the depression and bolted to the frame, as shown in Fig. 6 of the drawings.

Other modifications in regard to the detail construction of the truss b and journal-box c will readily suggest themselves to an experienced mechanic, and therefore we do not limit ourselves to any specific form of said parts, the salient features of our invention being the opening or depression d in the top of the side wall of the frame A and the detach-

able connection to said frame of the axial support of the couch-roll, which greatly facilitates the operation of applying or replacing the endless wire-cloth to the couch-roll.

55

What we claim as new, and desire to secure by Letters Patent, is—

1. In a Fourdrinier machine, the combination of the frame formed with a depression in the top of its side wall under the axis of the lower couch-roll, and an axial support for the couch-roll detachably connected to the frame to allow the wire-cloth to be removed from and replaced on the couch-roll without the necessity of lifting the said roll above the top 65 of the frame, as set forth.

2. In a Fourdrinier machine, the combination of the frame formed with a depression in the top of its side wall directly under the axis of the couch-roll, a truss across said depression and detachably seated on the frame, and a journal-bearing for the axis of said couch-roll on the said truss, as set forth. 7c

3. In a Fourdrinier machine, the combination of the frame formed with a depression in the top of its side wall directly under the axis of the lower couch-roll, a truss spanning said depression and seated on the frame removably sidewise therefrom, detachable fastenings retaining the truss on the frame, and a journal-bearing for the couch-roll detachably mounted on the truss, as set forth. 75

4. In a Fourdrinier machine, the combination of the frame formed with a depression in the top of its side wall directly under the axis of the couch-roll, a truss spanning the said depression and seated on the frame removably sidewise therefrom and provided with a socket in its top, detachable fastenings retaining the truss on the frame, and a journal-box for the couch-roll mounted on the truss and provided on its bottom with a hub entering the aforesaid socket, as set forth. 85

In testimony whereof we have hereunto signed our names this 21st day of November, 95 1890.

THOMAS H. LATIMER. [L. S.]
FRANK A. FLETCHER. [L. S.]
